(57) **CLAIM**

The ornamental design for a fuse switch disconnector, as shown and described.

DESCRIPTION

FIG. 1 is a front view of an embodiment of a fuse switch disconnector;

FIG. 2 is a rear view thereof;

FIG. 3 is a bottom view thereof;

FIG. 4 is a top view thereof;

FIG. 5 is a right side view thereof;

FIG. 6 is a left side view thereof; and,

FIG. 7 is a right side perspective view thereof.

The broken lines shown throughout the views represent the portions of the fuse switch disconnector that form no part of the claimed design.
